UNITED STATES PATENT OFFICE.

WILLIAM KELSO, OF PITTSBURG, PENNSYLVANIA.

CAR-COUPING.

No. 832,980.

Specification of Letters Patent.

Patented Oct. 9, 1906.

Application filed July 18, 1904. Serial No. 217,027.

To all whom it may concern:

Be it known that I, WILLIAM KELSO, a citizen of the United States, and a resident of Pittsburgh, in the county of Allegheny and State of Pennsylvania, have invented a new and Improved Car-Coupling, of which the following is a full, clear, and exact description.

My invention relates to car-couplings, my more particular object being to enable a number of movements to be controlled at will and to provide a number of improvements, as hereinafter described, and pointed out in the accompanying claims.

Reference is to be had to the accompanying drawings, forming a part of this specification, in which similar characters of reference indicate corresponding parts in all the figures.

Figure 1 is a fragmentary plan view of a coupling-head provided with my invention. Fig. 2 is a vertical section through the same, taken upon the line 2 2 of Fig. 3 looking in the direction of the arrow. Fig. 3 is a horizontal section upon the line 3 3 of Fig. 2 looking in the direction of the arrow. Fig. 4 is a perspective view of the sliding member used as a locking-pin. Fig. 5 is a section somewhat similar to Fig. 2, but showing the sliding member raised into a different position. Fig. 6 is a view similar to Figs. 2 and 5, but showing the sliding member 22 raised to its extreme upper position by means of the lifter 26; and Fig. 7 is a horizontal section upon the line 7 7 of Fig. 6 looking in the direction of the arrow.

The coupling-head is shown at 9 and is integrally provided with a barrel 8, with a vertical sleeve 10, and with a lug 11, this lug being disposed upon the interior of the barrel 8. The knuckle is shown at 12, and is mounted upon the pin 13. This knuckle is provided with shoulders 14, disposed adjacent to the ears 15, which are integral with the head 9. The knuckle 12 is provided with a wing 16, movable therewith, this wing having upon its under side a shoulder 17 of the shape indicated by dotted lines in Figs. 3 and 7. A bell-crank 18 is mounted upon a pivot 19 and is free to swing in a horizontal plane. This bell-crank is provided with a rounded surface 20 of the shape indicated in Figs. 5 and 6 and also with a rounded projection 21. This projection engages the shoulder 17, so that when the bell-crank 18 rotates partially upon the pivot 19 the projection causes the

knuckle 12 to swing open, as indicated in Fig. 7. The sliding member 22 answers the purpose of a locking-pin and is provided upon its upper end with flanges 23, integral therewith, so as to engage the upper surface of the sleeve 10, thereby acting as a limiting-stop for said sliding member. This sliding member 22 is provided with a recess 24 and with a web 25, as indicated more particularly in Fig. 2. A lifter 26 is provided with a toe 26^a and with a heel 26^b and is mounted upon a rod 27, which is connected with the uncoupling - lever (not shown) and may be thereby raised or lowered at the will of the operator. The sliding member 22 is further provided internally with a shoulder 28, serving as a limiting-stop for the heel 26^b when the lifter 26 is raised. The toe 26^a projects slightly under the bevel surface 10^a of the barrel 8, (see Fig. 2,) and thus locks the sliding member 22 against upward movement except when the lifter 26 is raised. The lifter 26 therefore performs the double function of locking the member 22 in a predetermined position, as indicated in Fig. 2, and of raising this member into two other positions, as indicated, respectively, in Figs. 5 and 6.

The sliding member 22 is still further provided with a pin 28^a, having a prop 29 integrally connected therewith and movable upon the same as a pivot. This prop is of the shape indicated in Figs. 2, 3, and 5 and is provided with a substantially wedge-shaped point 30, which is adapted to engage a recess 31 in the bottom of the barrel 8. This sliding member 22 is also provided at its lower end with a mutilation 34, whereby the member 22 is adapted to clear the rounded surface 20 of the bell-crank 18. The wing 16 is provided with a bevel 32 of a conformity approximating that of the upper end of the prop 29, as indicated in Fig. 2, and also with a curved facet or bevel 33.

The operation of my device is as follows: The several parts normally occupy the positions indicated in Figs. 1, 2, and 3, which represent the coupler in such condition that the knuckle 12 is closed—that is, the knuckle occupies the position which it usually occupies when it is ready for pulling cars. If now it be desired to uncouple the cars, the trainman raises the lifter 26 by means of the rod 27, thereby carrying upward the sliding member 22 into the position indicated in Fig. 5. The prop 29 is thus raised from its position indicated in Fig. 2 to that indicated in

Fig. 5, the point 30 of the prop thereupon passing into the recess 31. The lifter 26 may now be released, whereupon it drops downward, resting loosely upon the web 25 and against the smooth inner surface of the sleeve 10. The knuckle 12 is now free to move outwardly for the reason that the upper end of the prop 29 has been raised out of the bevel 32, as will be understood from Figs. 3 and 5. The trainman may leave the parts in this position, so that when the cars are moved apart the knuckle 12 will be opened or moved into the position indicated in Fig. 7, thus severing the train. As the knuckle 12 swings open the wing 16 is moved angularly, so that the face 33 moves against the prop 29, as will be understood from Fig. 5, thus moving the prop 29 upon the pivot 28^a as a center, so that the point 30 of the prop is raised out of the recess 31, and the sliding member 22 descends by its own weight, so as to rest loosely upon the wing 16. The parts occupy this position so long as the knuckle 12 remains open. As the wing 16 moves still further around the sliding member 22 merely rests loosely upon it, being otherwise unsupported. If now the knuckle 12 be moved back into its position indicated in Fig. 3, the sliding member 22 drops to its position indicated in Fig. 2 and prevents further movement of the wing 16 in either direction, thereby holding the knuckle 12 rigidly in its closed or normal position. (Indicated in Figs. 1 and 3.) Suppose, however, (the parts being in the position indicated in Figs. 1, 2, and 3,) that the trainman desires to open the knuckle 12 rather than to leave the same in such position that it can be opened by the movements of the rolling-stock. To accomplish this, he raises the sliding member 22 to the point indicated in Fig. 6, this point being higher than the one indicated in Fig. 5. The prop 29 is thus raised into the position indicated in this view, Fig. 6, so that its upper and lower portions respectively engage the lug 11, which is stationary within the barrel 8, and the rounded surface 20, which is integral with the bell-crank 18. The pressure of the prop 29 against the rounded surface 20 of the bell-crank causes the bell-crank to swing angularly around upon the pivot 19, as will be understood from Fig. 7, so that the rounded projection 21 forces the shoulder 17 outward, thus opening the knuckle 12. If now the knuckle 12 be moved slightly backward or inward, the wing 16 again engages the prop 29, lifting the point 30 from the recess 31 and allowing the sliding member 22 to again rest upon the wing 16. The knuckle 12 being afterward closed, the sliding member 22 again drops into its lowermost position. (Indicated in Fig. 2.) This last-mentioned movement of the wing 16 restores the bell-crank 18 to its normal position for the reason that

the shoulder 17 moves against the rounded projection 21 and causes the bell-crank to swing radially upon the pivot 19.

The wing 16 is provided with a tail 16^a integral therewith, which passes through an aperture 16^b in the head 9 and serves to hold the wing in place in case the pin 13 happens to break.

I desire to state that the lifting device for the locking member subserves a very important additional function in the event of breakage of any of the devices ordinarily termed "draft-rigging," since in such event or when either of the coupling-heads breaks at the shank thereof, thus enabling one or the other of the coupling-heads to pull out beyond its normal position, the chain connection to the lifting device of the broken head will so operate the lifter as to lift or raise its locking member, thereby causing the knuckle of this particular coupling-head to be carried outwardly, and thus allowing the cars to separate, the broken coupling-head remaining on that one of the cars to which it belongs.

Having thus described my invention, I claim as new and desire to secure by Letters Patent—

1. In a car-coupling, the combination of a knuckle provided with a wing movable therewith, a movable locking member for temporarily holding said wing in a predetermined position, mechanism controllable by said movable locking member and adapted to actuate said wing for the purpose of causing the said knuckle to swing open, and means controllable at will for actuating said movable locking member, said means having a rearwardly extending portion adapted to engage with a portion of the coupling-head for preventing release of the locking member except by operation of said means.

2. In a car-coupling, the combination of a barrel provided with a recess, a knuckle pivotally connected with said barrel and provided with a portion having a bevel, a locking member movable into and out of the path of said movable member, and a prop mounted upon said locking member, said prop being provided with a portion to be engaged by said bevel, and also with a portion for engaging said recess.

3. In a car-coupling, the combination of a knuckle, a movable locking member for temporarily holding the knuckle in a predetermined position, and mechanism controllable by the movements of the locking member for swinging said knuckle to open position, said mechanism comprising a device pivoted to the locking member, a stationary abutment therefor, and a bell-crank lever.

4. In a car-coupling, the combination of a knuckle, a locking member for engaging and disengaging the same, said locking member being provided with a recess having an inner web on its base, a hollow head for supporting

the knuckle and said locking member, and provided with a sleeve for encircling the locking member, and a lifter freely located within said recess and formed at its lower end with a toe and a heel normally seating on opposite sides of said web.

5. In a car-coupling, the combination of a head provided with a sleeve and with a recess, a knuckle mounted upon said head and free to swing relatively thereto, a hollow locking member slidably mounted within said sleeve and adapted to restrict certain movements of the knuckle, said locking member being provided with an inner shoulder

and having an inner web on its base, and a lifter loose within the recess, shaped to fit the web and normally seated thereon, and provided with a projecting portion for engaging said shoulder to rigidly secure said locking member in a predetermined position.

20 In testimony whereof I have signed my name to this specification in the presence of two subscribing witnesses.

WILLIAM KELSO.
